UNITED STATES PATENT OFFICE.

WILLIAM PEARCE, OF AKRON, OHIO, ASSIGNOR TO THE B. F. GOODRICH COMPANY, OF NEW YORK, N. Y., A CORPORATION OF NEW YORK.

DESIGN FOR A GOLF-BALL.

46,778.

Specification for Design.

Patented Dec. 15, 1914.

Application filed June 22, 1914. Serial No. 846,691. Term of patent 14 years.

To all whom it may concern:

Be it known that I, WILLIAM PEARCE, a citizen of the United States, residing at Akron, in the county of Summit and State of Ohio, have invented a new, original, and ornamental Design for Golf-Balls, of which the following is a specification, reference being had to the accompanying drawing, forming a part thereof.

The drawing represents a side elevation of a golf ball showing my new design.

I claim:

The ornamental design for a golf ball as shown.

WILLIAM PEARCE.

Witnesses:

WALTER K. MEANS,

ILLA N. KIRN.
